SLUB CATCHER

Samuel L. Abbott, Wilton, N.H., assignor to Abbott Machine Co., Inc., Wilton, N.H., a corporation of New Hampshire

Continuation of application Ser. No. 296,693, July 22, 1963. This application Apr. 30, 1965, Ser. No. 452,292
7 Claims. (Cl. 28—64)

This application is a continuation of my application Serial No. 296,693, filed July 22, 1963 now abandoned.

This invention relates to slub catchers and although some of its features are of general applicability it is of greatest utility when incorporated in a so-called wide blade slub catcher. The term "wide" used with reference to the blades refers to width in the direction of travel of the yarn and hence indicates length of yarn passage of the device. Slub catchers of the wide blade type are intended to distinguish between yarn enlargements of different lengths, so as to break the yarn in the case of long enlargements and not break the yarn in the case of short enlargements. Accordingly the length of the yarn passage in the direction of yarn travel is made long enough, as by using two wide blades, to engage at one time the whole length of a fairly long enlargement. A typical length of yarn passage may be, for example, one inch, obtained by using two opposed blades each one inch wide.

Assuming that two slubs are of similar constitution but one has the full length of the yarn passage and the other has only half of such length the lateral squeezing together of the long slab would be expected to apply twice as much force to the blades as would the similar squeezing together of the short slab. Again, assuming that the coefficient of friction is the same in each case, the retarding force exerted on the longer slab would be expected to be twice as great as that exerted on the shorter slab. It would be desirable to cause yarn breakage in either such supposed case. However, there are some really short enlargements such as "nibs" which it is better to leave in the yarn than to remove and replace with knots, and it is accordingly desired to avoid yarn breakage in the case of unobjectionable short enlargements. The ability of wide blades to distinguish between enlargements of different lengths is discussed in U.S. Patent No. 1,905,259 of E. J. Abbott, and an improved form of slub catcher employing the wide blade principle is described and claimed in U.S. Patent No. 2,623,265 of said E. J. Abbott. Although the device of this latter patent has gone into extensive use, a difficulty still exists in the case of yarns containing synthetic fibers. These yarns are considerably harder to break than for example, worsted yarns. For instance, the break strength of Dacron may be about three grams per denier whereas that of worsted may be about one gram per denier. A blend of half Dacron and half worsted will thus be considerably harder to break than an equivalent all worsted yarn. The wide blade slub catcher can still discriminate as to length of enlargements under these more difficult conditions, but the catching action becomes less certain in the case of the smaller slubs. To remedy this it would be desirable to set the blades closer, but setting the blades close enough to catch all slubs with certainty causes the device to catch many short enlargements such as "nibs" which are relatively unobjectionable but which are relatively incompressible. This causes unnecessary yarn breaks.

The wide blade slub catcher in its improved form as disclosed in the latter of said E. J. Abbott patents has further advantages besides its ability to distinguish as to lengths of enlargement. Among these other advantages are very good accuracy of the yarn passage. This passage is determined in practice by grinding away a face portion of one of two blocks, and the block having a ground away

2

face portion is arranged to slide in firm engagement with the other stationary block so as to expose the ground-away face portion for cleaning. This sliding block can also be slid farther, for complete removal. Sliding blocks ground to various depths can be kept in stock, and to change the yarn passage from one setting to another, a sliding block ground to the appropriate depth is simply substituted. The fact that the block is marked with the dimension of resulting yarn passage gives assurance that the intended passage is provided.

10 The invention aims to retain the advantages of wide blade sliding block slub catchers, including particularly the feature of discriminating as to length of enlargements, but to make the action more certain in the case of slubs in strong yarns without causing breakage when unobjectionable enlargements appear.

15 In the wide blade sliding block slub catchers the compression of the slab has been by unyielding opposed blade faces. While the forces of reaction of the slab to lateral compression decrease with decrease in length of slab, they increase as an enlargement is less readily compressible. Consequently, a short enlargement, if hard, will tend to cause breakage.

20 In reexamining the wide blade sliding block slub catcher it can now be seen that it not only discriminates as to length but also as to resistance to compression. The effect of this latter type of discrimination could advantageously be reduced. Taking as an extreme case a hard knot, it would be a good thing if the inability of this hard 25 knot to be squeezed down to the normal thickness of the yarn would not result in breakage.

25 The present invention involves the thought that through the use of a slab-engaging member which is resilient transversely of its face, and can permit deformation of its face by yarn enlargements, the hardness and relative incompressibility of certain yarn enlargements becomes less of a factor.

30 In another aspect, the invention involves the thought that although resiliency of the slab-engaging member, as contrasted with rigidity, would imply for a given setting, less compression of a given slab, less retarding and less tendency to break the yarn, this latter tendency can be effectively offset by use of a closer setting. It is not any longer necessary to avoid settings that tend to compress the short hard enlargements.

35 In the drawings:

FIG. 1 is a fragmentary front elevation of a portion of a head of a traveling spindle winding unit including a slub catcher of the present invention;

40 FIG. 2 is a fragmentary view mainly in plan of the device of FIG. 1;

FIG. 2a is a fragmentary left side elevation, with some parts omitted, of the device of FIG. 1;

FIG. 3 is a horizontal section taken on the line 3—3 of FIG. 1;

45 FIG. 4 is a view similar to FIG. 1 but showing a further form of slub catcher of this invention;

FIG. 5 is a fragmentary view mainly in plan of the device of FIG. 4;

FIG. 6 is a fragmentary left side elevation, with some parts omitted, of the device of FIG. 4;

FIG. 7 is a horizontal sectional view, on an enlarged scale, taken on the line 7—7 of FIG. 4;

50 FIG. 8 is a vertical sectional view on an enlarged scale, taken on the line 8—8 of FIG. 6; and

FIG. 9 is a vertical sectional view on an enlarged scale, taken on the line 9—9 of FIG. 6.

55 The winding unit head will be assumed to be, for example, like that of the said Abbott Patent No. 2,623,265 and to have an apron plate 24 carrying yarn guide blocks 21 and 22 which establish a vertical path for the yarn Y (FIG. 2a).

The member of the slub catcher corresponding in position to the stationary block 40 of said Patent No. 2,623,265, and here referred to generally by the reference character 40, is affixed to the apron plate 24.

As in said patent a sliding block 41 is ground away at its right side at 42 to define the yarn passage between it and the non-sliding member 40, and the right face portion of the block 41 which is not ground away serves to space the opposed face portions of the yarn passage and define the clearance between them. The remaining right-hand surface of the block 41 except at 42 is firmly seated against the non-sliding member, being held so by the strongly spring-pressed plunger 48 of said patent. The sliding block is slideable on a plate 44, toward the observer in FIG. 1, to expose the ground away portion 42 for cleaning, and may be manually slid still farther for complete removal of the sliding block. As indicated above, the slub catcher differs from that of the patent by the member 40 presenting a resilient face to the yarn passage. In the device of FIGS. 1 to 3 the member 40 comprises a steel backing plate 50, a pad 51 of resilient material such as rubber, and a thin sheet 52 of steel of, for example, 0.0015 inch thickness, these parts being glued together. The dimensions of the yarn passage and the thin sheet 52 are necessarily exaggerated in FIGS. 2 and 3. Whereas, for a given yarn No. 46s Dacron-worsted, the slub catcher of said patent would not normally have a setting of less than 0.01 inch because of a tendency to catch short hard nibs at closer settings, the slub catcher of FIGS. 1 to 3 could well have a setting of 0.007 inch. This closer setting makes the slub-removing action more certain. The resilient face of the stationary block can be deformed by either a slub or a nib; the slub because of its greater length will be caught, but the nib can pass through without breakage.

By omitting the thin steel layer 52 in the device of FIGS. 1 to 3 and having the sliding block 41 abut against the rubber 51, the deformation is made easier. A similar result can be secured by forming the metal layer in sections which are successively encountered by an enlargement. This latter construction is embodied in the device of FIGS. 4 to 9. The device of FIGS. 4 to 9 also includes provision for regulating the deformability of the resilient face, and for pre-stressing the material which backs up this face so that this material is under a certain compressive stress in the normal condition of the device with no slub present.

Most of the parts in FIGS. 4 to 9 corresponding to those described in connection with FIGS. 1 to 3 will not be again described in detail, but merely designated by the same reference characters. The stationary or right hand member is formed of a steel backing plate 50a, a pad 51a of resilient material such as sponge rubber glued to the backing plate, and a face layer comprised for example of six adjacent flexible steel fingers 52a glued to the sponge rubber, the fingers 52a being in firm engagement with the sliding block 41 excepting where the sliding block is ground away at 42. The member comprised of parts 50a, 51a and 52a thus presents a resilient face to the yarn passage. This member is retained in a stationarily mounted block 55 of channel section having an opening 56 through its right face. In rear of the yarn passage, left face portions of the block 55, adjacent the top and bottom thereof, abut against the block 41 as seen in the sectional view of FIG. 9, but in the region of the yarn passage these face portions are cut back at 55a as seen in FIG. 8. This cutting back of the block 55 at the region of the yarn passage prevents catching knots between the rigidly opposed blocks 41 and 55.

A lever 57 pivoted at 58 extends through opening 56 in block 55 and bears against the plate 50a. An arm 57a of the lever 57 carries adjustably mounted thereon one or more weights 59. By change or adjustment of the weights a desired load can be imposed on plate 50a. This puts the rubber 51a under more or less compression, so as to vary the resistance to flexure of the fingers 52a.

It is desirable to form the fingers 52a of somewhat

thick stock than the metal layer 52 of FIGS. 1 to 3, and fingers of $\frac{1}{8}$ inch stock may be used. The sponge rubber 51a will, however, be softer than the rubber 51 of the device of FIGS. 1 to 3.

5 The device of FIGS. 4 to 9 can advantageously be run at a little closer setting than that of FIGS. 1 to 3, for instance at a setting of 0.006 inch for the same yarn mentioned above.

In each case one of the members presenting a face of 10 the yarn passage is resilient transversely of such face and may be deformed by yarn enlargements. Thus in the case of sufficiently short enlargements, relative incompressibility of the enlargement is less of a breakage-inducing factor than in prior wide blade devices.

15 It was previously considered necessary to have the two blocks of the wide blade slub catcher present square edges at the mouth of the yarn passage where the yarn enters between them, this in order to increase the difficulty of entrance of a slub. This had a tendency to catch 20 and roll back fibers and strip them from the running yarn. The closer setting that can be employed with the present device increases the difficulty of travel of a slub through the yarn passage and hence renders practicable an easier entrance into the yarn passage, which will reduce stripping off of fibers and will tend to hold them into the yarn. 25 Thus the entrance may be made easier by beveling the edge of block 41 at 41a at the entrance to the yarn passage as in FIG. 1 or by slightly rounding off the bottom left-hand corner of the lowermost finger 52a as in FIG. 8.

30 I claim:

1. A slub catcher including members presenting opposed faces and means spacing said faces to define a clearance between said faces to form a yarn passage, one at least of said members being resilient transversely of its 35 face at the yarn passage and said last named face being locally deformable by yarn enlargements.

2. A slub catcher as claimed in claim 1 in which said transversely resilient member includes a plurality of individually yieldable elements disposed in succession along 40 the yarn passage.

3. A slub catcher as claimed in claim 1 in which said transversely resilient member includes a body of compressible material, the slub catcher including means for applying a compressive force to said material in a direction 45 opposing opening of the yarn passage.

4. A slub catcher including members presenting opposed faces and means spacing said faces to define a clearance between said faces to form a yarn passage, one at least of said members being resilient transversely of its 50 face at the yarn passage and comprising thin metal at said face and compressible material backing up the thin metal, and said last named face being locally deformable by yarn enlargements.

5. A slub catcher including members presenting opposed faces and means spacing said faces to define a clearance between said faces to form a yarn passage, one at least of said members being resilient transversely of its 55 face at the yarn passage and comprising a plurality of flexible fingers disposed in succession along the yarn passage and compressible material backing up the fingers, and said last named face being locally deformable by 60 yarn enlargements.

6. A slub catcher including members presenting opposed faces and means spacing said faces to define a clearance between said faces to form a yarn passage, one at least of said members being resilient transversely of its 65 face at the yarn passage and comprising a plurality of flexible fingers disposed in succession along the yarn passage and compressible material backing up the fingers, 70 the slub catcher including means for applying a compressive force to said material in a direction opposing opening of the yarn passage, and said last named face being locally deformable by yarn enlargements.

7. A slub catcher including members presenting opposed faces and means spacing said faces to define a clear-

ance between said faces to form a yarn passage, one at least of said members comprising a plurality of individually laterally displaceable fingers disposed in succession along the yarn passage and compressible material backing up the fingers, thereby to permit a yarn enlargement to encounter the fingers successively in passing through the yarn passage.
